UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

TYPE-HOLDER.

No. 902,719.

Specification of Letters Patent.

Patented Nov. 3, 1908.

Application filed March 21, 1908. Serial No. 422,382.

To all whom it may concern:

Be it known that I, JOSEPH S. DUNCAN, a citizen of the United States, residing at Chicago, in the county of Cook and State of Illinois, have invented new and useful Improvements in Type-Holders, of which the following is a specification.

The object of this invention is to provide a type holder of simple and inexpensive construction and provided with means by which it can be readily engaged with a type frame or other device for carrying the holder.

The type holder is designed more especially for holding an address form and to be carried by a frame which may be arranged in a card index system and run through a machine for addressing envelopes, letters or other matter but it may be used for other purposes to which it is or may be readily adapted by those skilled in the art.

The type holder may be provided with any desired number of type grooves and for the purposes of this application I have shown the holder with three grooves in the accompanying drawings, in which

Figure 1 is a plan view of the holder. Fig. 2 shows the closed end of the holder. Fig. 3 is a sectional view on the line 3—3 of Fig. 1 showing the open end of the holder.

The type holder 4 is stamped from a single sheet of metal and is provided with a plurality of type grooves 5. The holder may be formed with type grooves in any suitable manner as, for example, in accordance with my Patent No. 881,467 dated March 10, 1908 but as the particular shape of the groove constitutes no part of the present invention it will not be necessary to enter into a detail description thereof. At one end of the holder the metal is bent transversely across the type groove to form a stop 6 to close that

end of the groove while the other end 5' of the groove is open. The type are set in the holder by sliding them into the grooves through the open end 5' thereof or by inserting them into the grooves between the ends thereof and the type may be pushed up against the stop or not as desired.

At each end of the type holder there is an outwardly projecting lip 7 which is adapted to be engaged with some part of a frame to secure the type holder in place on the frame. This lip preferably extends outward from the back of the holder, otherwise the bottom of the type groove, in the direction of the length of the holder and I may provide one lip at each end of each type groove as shown in Fig. 1 or otherwise construct and arrange the lips providing always for at least one lip at each end of the holder.

My improved type holder can be easily and inexpensively made by stamping it from a single sheet of metal and the outwardly projecting lips adapt it to be readily engaged with flanges or other parts of a frame to receive the holder.

What I claim and desire to secure by Letters Patent is:

A type holder stamped from a single sheet of metal and having a plurality of parallel type grooves, one end of each groove being open, the metal at one side of each groove being bent transversely to form a stop at the other end of each groove, and a lip projecting outward from the bottom of each groove at each end thereof and beyond the stop at one end.

JOSEPH S. DUNCAN.
